BICYCLE SEAT

George Barris, North Hollywood, Calif., assignor to
Stelber Cycle Corporation, Elmhurst, N.Y., a cor-
poration of New York

Filed May 31, 1968, Ser. No. 12,153

Term of patent 14 years

U.S. Cl. D90—16
Int. Cl. D12—11, 14

FIG. 1 is a side elevational view of a bicycle seat showing my new design;

FIG. 2 is a top plan view thereof; and

FIG. 3 is a front elevational view thereof.

The bottom and rear surfaces are flat and plain.

I claim:

The ornamental design for a bicycle seat, as shown and described.
